INKSTAND

Frank M. Ashley, Great Kills, N. Y., assignor to
Lewis Gompers, as trustee

Application April 27, 1938, Serial No. 204,577

8 Claims. (Cl. 120—60)

My invention relates to inkstands.

The object of my invention is to provide an inkstand in which the ink is held in the upper side of the reservoir by a cup supplied with ink from the reservoir and positioned in easy reach of a pen which the inkstand is designed to support, the lower end of the pen-holder serving as a closure for the inkstand dip-tube in which it rests.

10 A further object is to provide an inkstand the novel parts of which may be located in the body portion of glass heretofore made and marketed, whereby the cost of new molds may be avoided.

15 A further object is to provide an inkstand comprising hard plastic material such as hard vulcanized rubber, a portion of which serves as a cover for the reservoir and fits in air-tight relation thereto, and to provide said cover with an air vent to permit air to pass into and from 20 the reservoir to prevent changes in atmospheric pressure from increasing in the reservoir relative to the pressure exterior thereto, and to cover said vent to prevent dust from clogging it.

The vent also serves to prevent the ink from 25 spouting in the operation of filling the cup from the reservoir and also from rising in the dip-tube above the top rim of the cup.

Referring to the drawing which forms a part of the specification:

30 Fig. 1 is a vertical sectional view of an inkstand embodying my invention.

Fig. 2 is a transverse sectional view on line 2—2 of Fig. 1.

35 Fig. 3 is a view of the inner sleeve which carries the cup portion, the upper end of which is formed to support a pen-holder with the pen held in the ink in the cup.

Fig. 4 is a view of the outer sleeve portion in which the air vent is formed.

40 Fig. 5 is a vertical sectional view of the cup portion which is held by friction in the inner sleeve portion and readily removable therefrom, and which with the inner sleeve portion serves as a plunger to force ink into the cup in its downward movement.

45 Fig. 6 is a cross sectional view of a soft rubber ring shown on an enlarged scale to illustrate the curved inner rim of the ring.

50 10 indicates a body portion of molded glass and while in a heated condition the upper rim is turned inwardly to form a cover portion for the reservoir 11.

55 Resting on the dome or top portion 10' and tightly fitted in the opening 11 is an outer sleeve 12 the upper inner side of which is enlarged in

diameter as illustrated at 13 to serve as an overflow chamber for ink which may be forced upwardly from the reservoir into the annular space 13 from between the outer sleeve 12 and inner sleeve 14 which fits therein in close sliding relation.

The inner sleeve is formed with a conical dip-tube 15, and a soft rubber ring 16 is held in position at its lower end by the upper end of the rim of the cup 17.

The rubber ring is formed with a curved inner edge 16' having a diameter such as to embrace the lower end of a pen-holder 18 illustrated in dotted lines in Fig. 1 and serving as a cork for the cup.

A very small capillary vent passage 19 extends vertically thru the upper flange portion of the outer sleeve and is normally covered by the flange portion 14', but not closed thereby.

The cup 17 is provided with a groove 18 in its outer wall which leads from its lower end to a transverse opening 18' leading into the cup chamber 20.

Both sleeve portions extend nearly to the bottom of the reservoir as illustrated.

The operating parts are preferably made of hard rubber or other suitable plastic material or of glass.

The reservoir is easily filled without the necessity of loosening or removing the outer sleeve 30 from its air-tight position in the dome.

To fill the reservoir, the inner sleeve is removed from the outer sleeve and ink is poured into the reservoir thru the outer sleeve until the reservoir is about half full, the air in the reservoir escaping thru the air-vent 19, and on replacing the inner sleeve, ink is forced from the reservoir thru the passages 18 and 18' into the cup, and during this operation the ink is prevented from spouting upwardly and thru the dip-cup by reason of a portion of the air escaping thru the vent and reducing the pressure above the ink in the reservoir, as will be readily understood.

The reservoir may be filled by pouring ink 45 directly into the dip-tube and overflowing from the cup into the passages 18' and 18, the air escaping thru the vent tube as the ink enters the reservoir.

50 It will be obvious that an air vent might be provided by making the outer sleeve a loose fit in the top of the stand but this method of control has not been satisfactory, first because it cannot be cleaned easily and also because it is not an 55

easy matter to make the leakage area a definite area to operate correctly.

To control an air vent by an automatic check valve has also proved unsatisfactory for the reason that the valve often sticks in its closed position; also that it is expensive to construct if made large enough to operate correctly.

As constructed, no dust enters the vent and it very seldom requires cleaning since it is automatically cleaned by the air forced therethru in the act of forcing ink from the reservoir to the cup.

All of the parts are durable and the device is simple to operate in filling the cup, all that is necessary to do is to lift the inner sleeve about a distance equal to half its length and release it and its weight will cause it to descend to its normal position of rest and fill the cup in its movement.

Having thus described my invention I claim as new:

1. An inkstand comprising a body portion having a reservoir for ink therein, an outer sleeve member fitted in the upper side thereof in air-tight relation, an inner sleeve fitted to slide closely in said outer sleeve and formed to provide a dip opening in its upper end adapted to support a pen-holder, a cup for ink carried by said inner sleeve and located below said dip opening, said construction embodying a passage leading from the reservoir directly to the upper end of said cup in open communication therewith at its upper end only.

2. The construction defined in claim 1, together with; said construction embodying an air-vent leading from said reservoir to the atmosphere, said vent being of small area and serving to prevent increase of pressure above that of the atmosphere in said reservoir.

3. An inkstand comprising a body portion having a reservoir for ink therein, an outer sleeve

member fitted in air tight relation in the upper side thereof, an inner sleeve fitted to slide closely in said outer sleeve and having a dip opening in its upper end, a cup for ink carried by said inner sleeve and located below said dip opening, a soft yielding ring located between the upper end of the cup and lower end of the dip opening, and a passage leading from the lower side of the reservoir directly to the upper end of the cup in open communication therewith at its upper end only to lead ink into said cup.

4. The construction defined in claim 3, together with; said outer sleeve having an air vent of small area serving to prevent increase of pressure in the reservoir above that of the atmosphere.

5. The construction defined in claim 1, together with; said cup being held in said inner sleeve by friction and readily removable therefrom.

6. An inkstand comprising a body portion having a reservoir for ink therein, an outer sleeve member fitted in the upper side thereof in air-tight relation and having a laterally extending flange provided with an air vent of small area, an inner sleeve fitted to slide closely in said outer sleeve and formed with a dip opening in its upper end, a cup for ink carried by said inner sleeve, said inner sleeve formed with a laterally extending flange which overlies the vent formed in the outer sleeve and partially closes it; said construction embodying a passage for ink leading from the reservoir directly to the upper end of the cup in open communication therewith at its upper end only.

7. The construction defined in claim 6, together with; said cup being carried by said inner sleeve in removable relation therewith.

8. The construction defined in claim 6, together with; said passage being formed between said inner sleeve and the outer wall of said cup.

FRANK M. ASHLEY.
